F. EBERHART

CAN WASHING AND DRYING MACHINE

Filed June 29, 1921

UNITED STATES PATENT OFFICE.

FELIX EBERHART, OF NEWARK, NEW JERSEY, ASSIGNOR TO AMERICAN CAN COMPANY, OF NEW YORK, N. Y., A CORPORATION OF NEW JERSEY.

CAN WASHING AND DRYING MACHINE.

Application filed June 29, 1921. Serial No. 481,225.

To all whom it may concern:

Be it known that I, FELIX EBERHART, a citizen of the United States, residing in Newark, in the county of Essex and State of New Jersey, have invented a new and useful Improvement in Can Washing and Drying Machines, of which the following is a specification.

My invention relates in general to means for cleansing filled cans and like articles, and has more particular reference to a machine in which the cans are both washed and dried by a positive wiping action.

It has been found that in the packing of certain types of products, such as syrup, the exterior of the containers becomes sticky and soiled and that the mere application of water thereto is not sufficient to properly cleanse the same. It is a principal object of my invention to provide means for positively wiping the containers during the time that washing water is applied thereto.

It has also been a common experience, particularly in the case of packing lithographed or decorated cans, to have the surfaces thereof marred or watermarked when the cans are dried by air alone. It is a further object of this invention to provide means for obviating this difficulty by positively wiping the washed cans immediately upon their being passed from the washing part of the machine.

Still another object of the invention is the provision in a machine of this character of means for blowing hot air upon the drying device and the washed cans as said cans are moved by a conveyor through the drying portion of the machine.

A still further object of the invention is the provision of associated washing and drying machines in which the water is pumped to the washing stations and hot air is blown upon the cans and drying devices through the instrumentality of common power means.

Another object of the invention is the provision in a machine of this character of means whereby said power devices also drive the drier conveyor.

Numerous other objects and advantages of the invention will be apparent as it is better understood from the following description, which, taken in connection with

the accompanying drawings, discloses a preferred embodiment thereof.

Referring to the drawings;

The figure is a side elevation of a combined washing and drying machine embodying the principles of my invention.

It will be noted that the embodiment of the invention shown by way of illustration in the drawing, comprises primarily a washing machine, indicated generally by the reference character 11, and a drying machine, similarly indicated by the reference character 12. The structure is supported by uprights 13 and 14 at opposite ends of the machine, and by a central supporting member 15, which also serves generally to connect the two parts of the machine. The uprights and supporting member are connected together by means of a base 16, and upon one section of this base is a tank 17 having one section 18 for containing clean water, and another section 19 adapted to receive the waste water after the washing operation. An inlet pipe 21 extends from a source of supply into the clean water tank, and a pipe 22 leads from a suction head 23 within said tank to a pump 24. An overflow pipe 25 is positioned within this tank and adapted to serve as an outlet when the water exceeds a certain depth. By means of the pump 24 the water is forced through connecting pipes 26 and 27 to a spray pipe 28. Branch pipes 30 and 30' are provided with shut-off valves 40.

The filled cans 29 are placed in any suitable or desirable manner upon an inclined track 31 having guides 32, between which the cans roll by gravity. Near the receiving end of the machine and positioned above the track 31 are two sprays 33 adapted to thoroughly moisten the cans to be washed. These sprays are upon the pipe 28, which has further along, other sprays 34 by means of which fresh streams of water are cast upon the cans at different points in their course of travel. Above and beneath the pipe 28 are bars 35 and 36 having at intervals therein pins or rods 37 and 38 respectively, and suspended from the rods 37 are wipers 39 consisting of folded flannel rags or other suitable material. Flexible brushes could also be substituted for the wipers in cases where a stiffer wiper was desired. It will

be noted that these wipers are deposited above and against the pins or rods 38 and that they are positioned in proximity to the sprays in such manner that they will be constantly kept moist thereby.

As the cans advance upon the track 31 the sprays play upon them and upon the wipers which absorb sufficient water to become quite heavy. As the cans come in contact with the pass beneath the wipers they are thoroughly washed by a positive wiping action and, so cleaned, are delivered from the lower end of the track 31 to a drier conveyor 41.

15 The waste water is directed by means of guides 42, 43, and 44, into the tanks 18 and 19, that which first strikes the cans and carries the greater part of the dirt therefrom being directed into the waste tank 19, 20 it being understood that it may be cleaned and utilized an indefinite number of times. An outlet 46 from the waste tank is provided so that the water may be drawn off when desired.

25 As previously stated, the washed cans are delivered to a conveyor 41 which conveyor has channel guides 47 and is formed with triangular stops or supports 48 which engage and support the cans. The conveyor 30 41 is inclined upwardly from its receiving end and is supported upon a frame 49 which is adjustable at its lower end by means of a slot 51 through which a bolt or other fastening member 52 extends. Bars 53 and 54, 35 similar to the bars 35 and 36 upon the washing section of the machine, are positioned above the conveyor 41, and wipers 55 are suspended from the bar 53, as in the other section of the machine. As the cans are moved upwardly they engage and are wiped by these wipers and thereby thoroughly and evenly dried. The contact with the wipers will turn or roll the cans, thereby wiping all portions thereof. A hot air blower 56 40 45 is suitably secured above the wiper bars and serves to blow hot air upon the wipers and the cans whereby they are quickly and completely dried.

50 A motor 57 serves to drive a shaft 58 carrying a pulley 59 and operating the pump 24 and the conveyor 41 by means of belt connections 61 and 62. Air is fanned through the pipe 63 to the blower 56.

55 It will be understood that this machine is adapted to receive the cans immediately after their leaving a closing machine, where the soiling usually takes place; and that the cans may be discharged from the drying apparatus onto a discharge conveyor 64 which is driven by a belt 65 and may be arranged to lead to any desired point.

60 It is thought that the invention and many of its attendant advantages will be understood from the foregoing description, and it will be apparent that various changes may

be made in the form, construction and arrangement of the parts without departing from the spirit and scope of the invention or sacrificing all of its material advantages, the form hereinbefore described being merely a preferred embodiment thereof.

I claim:

1. A machine for cleansing cans and the like, comprising a track upon which the cans may move, means for moistening the can bodies as they enter upon said track, and loosely hanging moistened devices for conforming with the shapes of and wiping said bodies as they move along their path of travel.

75 2. A machine for cleansing cans and the like, comprising an inclined track upon which the cans may roll, means for spraying water upon the moving cans and a plurality of moistened cloth devices arranged along said track for wiping said can bodies.

80 3. In a machine for washing cans, the combination of means for rolling the cans along a prescribed path, soft absorbent wipers hanging in the path of the said cans, and spraying devices for spraying the traveling cans and also supplying water to and rendering heavy said absorbent wipers.

85 4. A machine for cleansing cans and the like, comprising means for advancing the cans by gravity, a plurality of sprays arranged successively for moistening the can bodies, and a plurality of soft and absorbent wipers associated with each of said sprays and moistened thereby for wiping 90 100 said advancing bodies.

5. A machine for cleansing cans and the like, comprising soft and absorbent wipers arranged to hang against and conform with the can surfaces for washing the can bodies, means associated therewith for receiving and advancing the washed cans, and fibrous drying means arranged beyond the sphere of the washing means and extending into the path of said advancing washed bodies 105 110 and adapted to wipe the moisture therefrom.

6. A machine for cleansing cans and the like, comprising means for washing the can bodies, means associated therewith for receiving and advancing the washed cans, and drying means arranged along the course of travel of said washed cans for wiping the moisture therefrom, said drying means including wipers and means for blowing hot air thereon and upon said cans.

115 7. A machine for cleansing cans and the like, comprising means for rolling the cans, devices for moistening the bodies of said cans and for wiping the surfaces thereof, 120 125 said devices comprising a plurality of sprays and flexible cloth wipers associated therewith and moistened thereby, in combination with means for advancing and drying the washed cans.

8. A can washing and drying machine, comprising in combination a washing device having means for advancing the cans, means for casting washing water thereon, 5 and cloth wipers for positively wiping the moistened cans, and a drying device adapted to receive and advance the washed cans and having means for drying said cans by a positive wiping action.
- 10 9. A can washing and drying machine, comprising in combination a washing device having means for advancing the cans, means for casting washing water thereon, and means for positively wiping the moistened cans, and a drying device adapted to receive and advance the washed cans and having means for drying said cans by a positive wiping action, and means for blowing hot air upon said wiping means and 15 the advancing cans.
- 10 10. A can washing and drying machine, comprising in combination a track for the cans to be washed, a carrier above the track, a tank adapted to contain washing water, 20
- means for pumping said water to the said carrier, spraying devices extending from said carrier and adapted to cast the water upon the advancing cans, wiping means moistened by said sprays and adapted to contact with said moving cans, means for receiving and advancing the washed cans, and drying means associated therewith and including means for contacting with and wiping the moisture from said advancing washed cans. 25
11. A can washing and drying machine, having in combination a declining can track, a tank beneath the same, means for applying water on the cans as they pass along said track, means for wiping the cans as they are wetted, an upwardly inclined track receiving the washed cans from said declining track, means for propelling the cans on said upwardly inclined track, drying wipers against which the cans are so 30 35 40 45 propelled, and means for blowing air on the cans being dried.

FELIX EBERHART.
